UNITED STATES PATENT OFFICE

ANDREW J. MALONEY, OF MERION, PENNSYLVANIA, ASSIGNOR TO THE PHILADELPHIA & READING COAL & IRON COMPANY, OF PHILADELPHIA, PENNSYLVANIA, A CORPORATION OF PENNSYLVANIA

ASH REMOVING APPLIANCE FOR FURNACES

Application filed October 7, 1929. Serial No. 397,834.

My invention relates to furnaces, particularly of the domestic furnace type, and has for its object to provide simple and efficient mechanism for automatically removing the 5 ashes from the ash pit. Broadly speaking, my invention consists in providing the furnace ash pit with a conduit through which air and ashes can be drawn from the ash pit, providing this conduit with a motor actuated 10 device to create a draft therethrough, providing in the ash pit a resiliently supported platform to receive and support the ashes and providing a controller actuated by the up and down movements of the ash supporting 15 platform and operating to start and stop the motor driven appliance for creating a draft in the conduit. By preference I also provide means for opening and closing the passage between the furnace proper and its 20 ash pit, said means being actuated by a solenoid magnet J, the starting and stopping of which is also controlled by the controller actuated by the resiliently supported platform.

My invention will be best understood as 25 described in connection with the drawing in which it is illustrated and in which

Figure 1 is an elevation, partly in section, showing my devices as applied to an ordinary type of domestic furnace.

Figure 2 shows a portion of the resiliently supported platform and the controller connected thereto, which in the illustrated construction is an electric switch.

Figure 3 is a view on a larger scale showing one end of the apron or partition, which in the illustrated construction is the appliance used for opening and closing the passage between the furnace and the ash pit, this view also showing an electric controller or 40 switch actuated by the movements of the apron and

Figure 4 is an enlarged view of the motor construction which is shown in Figure 1 as a device for actuating the apron.

A is the furnace; A¹ the furnace grate; A² the ash pit; A³ the damper door leading into the ash pit. A⁴ is a flue leading from the furnace to the stack A⁵. B and B¹ indicate the conduit for air and ashes drawn 45 from the ash pit and shown as connected with

an ash receptacle C. A continuation from the conduit leads from the ash receptacle as indicated at B² through a motor driven draft creating fan indicated at D, from which a further continuation of the conduit indicated at B³ leads to the open air. It is advisable that a screen be supplied to prevent the passage of light ash from the receptacle C and I have indicated such a screen at C¹. E is the platform located near the bottom of the ash pit and resiliently supported therein as by means of springs indicated at F. G is a flexible metallic apron carrying, as shown, a block G¹ at its free end, which slides in a groove a in the furnace wall. The other end of the apron is attached to a spindle H to which is also attached a gear wheel H¹. The apron may be made of such thin metal as is used in the construction of Farrand rules. I indicates a rack engaged with the gear wheel H¹ and normally drawn downward by the spring I¹, the effect of this downward movement being to coil the apron around the spindle. The upper end of the rack is actuated by the armature of a solenoid motor indicated at J and so arranged that when the solenoid is actuated the armature and the attached rack are drawn up with the effect of uncoiling the flexible apron and forcing it across the space between the furnace and the ash pit.

The main controller device consists of an electric switch indicated at K, connected as shown to the solenoid by wires K¹, the battery K² being located in the circuit. L indicates the second controller device, here indicated as an electric switch, which is closed by the contact piece l attached to the block G¹. This switch opens and closes the circuit wires indicated at L¹, which in turn connect with the motor of the motor actuated fan D. The battery of this circuit is indicated at L².

In operation the motor driven draft appliance is normally idle and the solenoid unenergized. Ashes gradually accumulate on the resiliently supported platform E, gradually depressing it as the ashes accumulate until finally the electric switch K is closed, whereupon a current is established through the solenoid which draws up the rack, uncoils the

flexible apron and forces it across the space between the furnace and the ash pit. At or near the close of this movement the switch L, l is closed and a current established through the motor D of the draft appliance, the starting of which creates a draft through the ash box, which carries the ashes accumulated on the platform into and through the conduit B and B¹ into the ash receptacle C, the air passing from the ash receptacle through the motor driven fan to a point of escape.

It will be obvious that as the ashes are carried away from the platform the platform will rise, opening the controller switch K, which will deenergize the solenoid J, whereupon the spring I¹ will retract the flexible apron, by means of the rack I and spindle H¹ opening the controller switch L, l, which will deenergize the motor drive draft appliance D.

Having now described my invention, what I claim as new and desire to secure by Letters Patent, is:

1. In combination with a fire box and an ash pit located to receive ashes therefrom, a conduit for air and ashes connected to the ash pit, motor actuated means for creating a draft through the conduit and ash pit, resiliently supported means for receiving and supporting ashes in the ash pit, means for starting and stopping the motor actuated draft creating means including a controller actuated by the up and down movements of the resiliently supported ash receiving support, means for opening and closing the connection between the fire box and ash pit, and mechanism for actuating said last named means controlled by the controller.

2. A furnace appliance as called for in claim 1, in which the means for starting and stopping the motor actuated draft creating means includes a second controller actuated by the movements of the opening and closing means and controlling in turn the starting and stopping of the motor actuated draft device.

ANDREW J. MALONEY.
